UNITED STATES PATENT OFFICE.

WILLIAM S. GRAFTON, OF WHEELING, WEST VIRGINIA, ASSIGNOR TO THE WHEELING CORRUGATING COMPANY, OF SAME PLACE.

DESIGN FOR A METALLIC FINISHING-PLATE.

SPECIFICATION forming part of Design No. 23,045, dated February 6, 1894.

Application filed January 8, 1894. Serial No. 496,191. Term of patent 7 years.

To all whom it may concern:

Be it known that I, WILLIAM S. GRAFTON, a citizen of the United States, residing at Wheeling, in the county of Ohio and State of West Virginia, have invented and produced a new and original Design for Metallic Finishing-Plates, of which the following is a specification, reference being had to the accompanying drawing, forming part hereof, which shows a metallic finishing-plate or ceiling-plate designed according to my invention.

My design consists of a square or rectangular finishing plate A, divided into equal parts or sub-divisions B, by ribs or ridges a a' , extending from one side of the plate to the other, and crossing each other at right angles. At the intersections of the ribs a a' , there are circular convex projections a^2 , with concave centers.

In each of the sub-divisions or squares B, bounded by the ribs a a' , there is an ornamentation in relief. There are four different kinds of ornamentations shown, but they are symmetrically arranged throughout the plate.

There are sixteen sub-divisions B shown, and in each four subdivisions or squares B in each horizontal row there is one of the several ornamentations.

In square No. 1, at the left-hand side of the top row of subdivisions, the ornamentation consists of a circular, convex projection C, having a relatively small convex projection c, from which radiate a series of concave pear-shaped arms c' .

In square No. 2, there is a circular projection d, around which are arranged a series of rectangular ribs d' . Four spoon-shaped pro-

jections d^2 radiate from the center, and cross the ribs d' . Each of the spoon-shaped projections d^2 has two oblong concave portions d^3 . 40

In square No. 3, there is a central, convex, circular projection e, from which radiate in curved lines a series of gourd-shaped projections e' , the outer ends of which are inclosed by a circular rib e^2 . 45

In square No. 4, there is a central circular projection f, from which radiate four arms f' , forming a St. Andrew's cross. The arms, however, are pointed at their outer ends, and the lines are curved. Each arm has two oblong depressions f^2 . There are four heart-shaped projections f^3 , arranged between the arms. 50

Similar ornamentations to the four ornamentations just described are arranged in the other twelve squares, or sub-divisions, but they are arranged in a different order, similar designs or ornamentations being arranged in series diagonally across the plate. 55

The essential feature of my design, is a metallic finishing plate sub-divided by ribs or ridges crossing each other and the subdivisions being ornamented with designs of different configuration, as shown in the drawing and above described. 60

I claim—

The design for a metallic finishing plate herein shown and described.

In testimony whereof I have hereunto subscribed my name.

WILLIAM S. GRAFTON.
